UNITED STATES PATENT OFFICE.

SIGMUND FISCHER, OF PROVIDENCE, RHODE ISLAND.

DESIGN FOR A STONE MOUNTING.

Application filed July 22, 1926. Serial No. 18,462. Term of patent 7 years.

To all whom it may concern:

Be it known that SIGMUND FISCHER, a citizen in the United States, residing at Providence, of the county of Providence and State of Rhode Island, has invented a certain new, original, and ornamental Design for Stone Mounting, of which the following is a specification, reference being had to the accompanying drawing, forming part thereof.

Fig. 1 is a plan view of a stone mounting embodying my design.

The ornamental design for a stone mounting substantially as shown.

In testimony whereof I affix my signature.

SIGMUND FISCHER.
